ELECTROLYTIC CELL AND METHOD OF MAINTAINING THE EFFICIENCY THEREOF.

1,145,593.

Specification of Letters Patent.

Patented July 6, 1915.

Application filed March 2, 1914. Serial No. 821,978.

To all whom it may concern:

Be it known that I, WILLIAM M. JEWELL, a citizen of the United States, residing at Chicago, in the county of Cook and State of Illinois, have invented certain new and useful Improvements in Electrolytic Cells and Methods of Maintaining the Efficiency Thereof, of which the following is a specification, reference being had to the accompanying drawings.

My invention relates to electrolytic cells, and is of especial utility in connection with cells of the character shown and described in Letters Patent No. 1,056,181, granted to me March 18, 1913, in which the portions of the electrolyte surrounding the anodes and cathodes, respectively, are of different specific gravities, the anode liquor being the heavier so that the cathode liquor is, in a sense, carried by the anode liquor, the stratification of the anode and cathode liquors being preserved by supplying a suitable liquid to the cathode liquor, as required, to keep it lighter than the anode liquor.

In the operation of cells of this character, I have discovered that the efficiency of the cell, in the course of time, tends to deteriorate owing to the formation of hypochlorites or chlorates in the anode liquor, due, apparently, to the migration of the hydroxyl ions which are being constantly carried toward the anodes. The graphite elements composing the anodes are very readily oxidized and destroyed in the presence of hypochlorites or chlorates. I have discovered, further, that the deterioration referred to may be, to a large extent, if not altogether, prevented and the efficiency of the cell very markedly increased, by maintaining a flow of anode liquor from the lower portion of the anode chamber toward the lower portion of the cathode chamber, and particularly below the cathodes therein, this liquor being then withdrawn from the cell and treated to replenish its saline constituents, after which it is returned to the anode chamber. The latter step, while advantageous from the standpoint of economical operation of the cell, is not essential to the generic idea of causing the liquor from the anode chamber to flow toward the cathode chamber and then out of the cell so as to maintain a definite flow of the liquor from the anode chamber toward the cathode chamber. The best results are obtained by maintaining a flow of the liquor

through the lower portions of the anode and cathode chambers, then out of the cell and back to the anode chamber after replenishment of its salient constituents; but very satisfactory results are obtained by maintaining such circulation without restoring the strength of the liquor, and also by maintaining the flow from the anode to the cathode chamber and then out of the cell without returning the liquor to the cell. I believe the increased efficiency of the cell due to this mode of operation is due to counteraction of the migration of the hydroxyl ions from the cathode toward the anode chamber, but the fact is, that by the operation described the tendency to form hypochlorites or chlorates in the anode liquor is, to a large extent, if not entirely, overcome and the efficiency of the cell very greatly increased.

In addition to the method described, which forms an important feature of my present invention, my invention also includes the construction of the cell by which the method is carried out or performed in an efficient manner, and the operation of the cell is in other respects also improved.

In the accompanying drawings, in which I have applied my improvements to a cell of the general construction shown in Figures 4, 5 and 6 of my said Patent No. 1,056,181, Fig. 1 is a partial, longitudinal section of my improved cell, taken on line 1—1 of Fig. 3; Fig. 2 is a transverse section, on line 2—2 of Fig. 1, partly broken away; Fig. 3 is a partial plan view, the electrodes being in section; Fig. 4 is a view illustrating one of the anode units; and Fig. 5 is a bottom view of the anode unit shown in Fig. 4.

Referring to the drawings,—6 indicates the bottom, 7—8 the side walls, and 9 one of the end walls of the cell, these parts being preferably made of soapstone, or other suitable material.

10—11 indicate two longitudinally-extending partitions, also of soapstone, which are disposed adjacent to the side walls 7—8, respectively, as best shown in Figs. 2 and 3. The space between the partitions 7 and 10 constitutes a chamber A which, in the operation of the cell, contains a caustic solution, such as sodium hydrate, and into which also the gases generated at the cathodes pass. The space between the wall 8 and the partition 11 is divided by a hori-

zontal partition 12 into an upper chamber B and a lower chamber C. The upper chamber, in the operation of the cell, is adapted to contain a substantially saturated 5 solution of brine, which constitutes the electrolyte, and is connected with the anode chambers hereinafter described by passages 13, as shown in Fig. 3. The chamber C is adapted to contain spent brine and is connected with the lower portion of the electrolytic chamber by pipes 14, the arrangement of which will be hereinafter more particularly described.

15 indicates an outlet pipe leading from 15 the lower portion of the chamber C, and 16 indicates an inlet pipe leading to the lower portion of the chamber B.

As shown and described in my patent hereinbefore referred to, the spent brine 20 passing out of the chamber C is conducted through a suitable apparatus where it takes up a fresh supply of salt so that it is restored to the proper strength and is then reintroduced through the chamber B. As 25 such brine-strengthening apparatus is fully described in my said patent, it is not illustrated herein.

17 indicates a series of vertically-disposed partitions which extend transversely 30 of the cell between the partitions 10—11, separating the same into a number of separate compartments, each of which is adapted to contain an operating cell unit comprising anode and cathode chambers.

35 18 indicates a number of shorter partitions extending downward from the upper part of the cell to a point near the bottom thereof, which divides the several compartments into anode chambers 19 and cathode 40 chambers 20, as best shown in Fig. 1.

21 indicates the anodes, which extend down into the anode chambers, each of said chambers containing a plurality of anodes in the form of rods, of carbon or other suitable material, the several anodes in each chamber being connected to a common supporting slab or bar 22, which is also preferably made of carbon and not only supports the anodes but forms a cover for the 45 anode chamber. The anodes are preferably secured to the bar 22 by providing them with screw threads so that they may be screwed into threaded sockets in said bar, as best shown in Fig. 2. The arrangement 50 of the several anodes forming each unit is best shown in Fig. 4.

23 indicates the cathodes, which are substantially like the anodes and are made of the same material but are somewhat shorter 55 so that they do not project down into the cathode chamber as far as the anodes project into the anode chamber, as is best shown in Fig. 1. The cathodes of each unit are secured to a supporting-bar 24, which forms a 60 cover for the cathode chamber, so that the

several bars 22 and 24 together serve to form a cover for the cell as a whole.

As best shown in Fig. 1, the pipes 14 which lead to the spent brine chamber C, are placed in the several cathode chambers 70 20 at a level below the lower ends of the cathodes therein and adjacent to the partitions 17 so that the anode liquor flowing from the several anode chambers is caused to flow toward the cathode chambers, and in the best embodiment of the invention, across the lower portions of said cathode chambers, before entering the pipes 14 through which it is conducted away for the replenishing treatment. The pipes 14 are placed low 80 enough so that this flow of anode liquor from the anode chambers is independent of the outflow of cathode liquor, which is otherwise provided for, and does not disturb or mingle with the liquor in the cathode 85 chambers to any material extent, and consequently is maintained comparatively free from the caustic solution formed in the cathode chambers. By instituting this flow of the liquor in the anode chambers, the 90 formation of hypochlorites or chlorates in the anode liquor, as hereinbefore explained, is prevented, and the efficiency of the cell is very greatly increased. The liquor in the anode chambers is heavier than that in the 95 cathode chambers, and the relative specific gravities of these liquors is maintained from time to time, as may be necessary, by supplying water to the cathode chambers, preferably through funnels 25 provided for that 100 purpose.

26 indicates ducts leading from the upper portions of the several cathode chambers to the chamber A, as shown in Fig. 3, such ducts being provided to conduct the hydrogen formed in the cathode chambers into said chamber A, whence it may pass out through a pipe 27 provided for that purpose, as shown in Fig. 2.

28 indicates passages extending through 110 the partition 10 below the level of the liquor in the cathode chambers for conducting the caustic solution into the chamber A.

29 indicates an outlet pipe leading from the upper portion of the chamber A, which 115 pipe is placed at the level at which it is desired to maintain the liquor in the cathode chambers.

30 indicates ducts leading from the upper portion of the anode chambers to the upper 120 portion of the chamber B for conducting chlorin from said anode chambers to the chamber B, and 31 indicates a discharge pipe leading from the chamber B for the discharge of the chlorin therefrom.

By circulating the anode liquor in the manner described, a very rapid rate of flow can be maintained without adding any appreciable amount of salt or chlorin to the cathode products, and I am able to obtain 130

very high efficiencies both in chlorin and caustic soda production, using an electrolyte consisting of a saturated solution of common salt. Of course, the cell may also be 5 used with some other electrolyte and with electrodes of other materials, depending upon the products which it is desired to produce.

By using anode and cathode elements arranged vertically, in the manner described, I also obtain much better results than where horizontal electrodes are used, as the electrode area, being substantially vertical, the 10 gaseous products of the electrolysis are very 15 readily eliminated and do not adhere to the electrodes. A further advantage in using cathode elements of this form is that only a very small percentage of the caustic soda is produced in the lower portion of the cathode 20 chambers, and therefore the cathode liquor has less tendency to become saturated and gravitate toward the bottom of the cell or to flow toward the anode compartments. Where horizontal electrodes are used, the 25 gases do not readily pass off as formed, thus increasing the resistance of the cell and lowering its efficiency; also with horizontal cathodes the tendency is to produce a heavy caustic liquor at or below the lower portions 30 of the cathodes, leaving the cathode liquor above the cathodes comparatively light. If this condition is allowed to go on, the caustic liquor thus produced at the under sides of the cathodes becomes heavier than the brine 35 and unless interfered with would find its way into the anode chambers where it would form hypochlorites or chlorates, with the objectionable results hereinbefore described.

By using electrodes consisting of a plurality of rods assembled in units as described, the electric current may travel from point to point, or end to end, of the graphite rods, and this by reducing the resistance in the cell produces better results and permits 45 of the substitution of conductive materials for the partitions 18 instead of partitions made of di-electric material, thereby increasing the efficiency of the cell by reducing 50 the resistance offered to the passage of the current from the anode to the cathode chambers.

While my improved cell may be very efficiently employed to generate chlorin gas and caustic solution, it may be used for any 55 other purpose to which it is adapted.

That which I claim as my invention, and desire to secure by Letters Patent, is,—

1. The method of maintaining the efficiency of an electrolytic cell of the type described, which consists in causing liquor from the anode chamber to flow toward the cathode chamber below the level of the cathode therein, and then out of the cell independently of the outflow of cathode liquor.

2. The method of maintaining the efficiency of an electrolytic cell of the type described, which consists in causing liquor from the anode chamber to flow into the cathode chamber below the level of the cathode therein, and then out of the cell independently of the outflow of cathode liquor. 70

3. The method of maintaining the efficiency of an electrolytic cell of the type described, which consists in causing liquor from the anode chamber to flow across the lower portion of the cathode chamber, and then out of the cell independently of the outflow of cathode liquor. 75

4. The method of maintaining the efficiency of an electrolytic cell of the type described, which consists in causing liquor from the anode chamber to flow toward the cathode chamber below the level of the cathode therein, and then out of the cell independently of the outflow of cathode liquor, and then re-introducing the liquor into the anode chamber. 80

5. The method of maintaining the efficiency of an electrolytic cell having anode and cathode chambers disposed side by side, and in which the electrolyte comprises a heavier anode liquor and a lighter cathode liquor, which consists in maintaining a flow of liquor from the lower portion of the anode chamber into the lower portion of the cathode chamber and then out of the cell independently of the outflow of cathode liquor. 90

6. The method of maintaining the efficiency of an electrolytic cell in which the electrolyte comprises a heavier anode liquor and a lighter cathode liquor, arranged in adjacent chambers, which consists in discharging liquor from the lower portion of the anode chamber through the lower portion of the cathode chamber independently of the outflow of cathode liquor, and then re-introducing it into the anode chamber. 105

7. The method of maintaining the efficiency of an electrolytic cell in which the electrolyte comprises a heavier anode liquor and a lighter cathode liquor, arranged in adjacent chambers, which consists in discharging liquor from the lower portion of the anode chamber through the lower portion of the cathode chamber, restoring the strength of the discharged liquor, and then re-introducing it into the anode chamber. 110

8. The method of maintaining the efficiency of an electrolytic cell having anode and cathode chambers disposed side by side, and in which the electrolyte comprises a heavier anode liquor and a lighter cathode liquor, which consists in maintaining a discharge of liquor from the lower portion of the anode chamber through the lower portion of the cathode chamber, restoring the strength of the discharged liquor, and then returning it to the anode chamber. 120

1
9. The method of maintaining the efficiency of an electrolytic cell having anode and cathode chambers disposed side by side, and in which the electrolyte comprises a 5 heavier anode liquor and a lighter cathode liquor, which consists in maintaining a discharge of liquor from the cell across the cathode chamber below the level of the cathode therein and independently of the 10 outflow of cathode liquor.

10. An electrolytic cell comprising anode and cathode chambers adapted to contain a heavier anode liquor and a lighter cathode liquor, an anode in the anode chamber, a 15 cathode in the cathode chamber, and means for causing liquor to flow from the anode chamber toward the cathode chamber below the level of the cathode therein and thence out of the cell independently of the outflow 20 of cathode liquor.

11. An electrolytic cell comprising anode and cathode chambers adapted to contain a heavier anode liquor and a lighter cathode liquor, an anode in the anode chamber, a 25 cathode in the cathode chamber, and means for causing liquor from the lower portion of the anode chamber to flow across the lower portion of the cathode chamber and then out of the cell independently of the outflow of 30 cathode liquor.

12. An electrolytic cell comprising anode and cathode chambers adapted to contain a heavier anode liquor and a lighter cathode liquor, the lower portion of the anode chamber communicating directly with the lower portion of the cathode chamber, an anode 35 in the anode chamber, a cathode in the cathode chamber, and an outlet communicating with the lower portion of the cathode chamber for causing liquor to flow from the 40

anode chamber into the lower portion of the cathode chamber and then out of the cell independently of the outflow of cathode liquor.

13. An electrolytic cell comprising a receptacle having anode and cathode chambers disposed side by side, a partition separating the upper portions of said chambers from each other and allowing communication between the lower portions of said 50 chambers, and depending rods in said chambers, respectively forming anodes and cathodes.

14. An electrolytic cell comprising a receptacle having anode and cathode chambers disposed side by side, a partition separating the upper portions of said chambers from each other and allowing communication between the lower portions of said 55 chambers, and depending rods in said chambers, respectively forming anodes and cathodes, the cathodes being shorter than the anodes, and an outlet communicating with the lower portion of the cathode chamber below the cathode therein.

15. An electrolytic cell, comprising anode and cathode chambers disposed adjacent to each other and having a communicating opening in the lower portions thereof, an anode and a cathode in said chambers, respectively, above said opening, and an outlet for the liquor communicating with the lower portion of the cathode chamber whereby liquor may flow from the anode to the cathode chambers, and then out of the cell.
